HEAT MOTOR OPERATED MECHANISM

Daniel G. Taylor, Minneapolis, Minn., assignor to
 Minneapolis-Honeywell Regulator Company,
 Minneapolis, Minn., a corporation of Delaware

Application February 26, 1942, Serial No. 432,448

13 Claims. (Cl. 137—139)

This invention is directed broadly to devices which are operated by means of a heat motor, and is more particularly concerned with a heat motor and associated mechanism for operating a pilot valve for controlling a diaphragm pressure operated valve.

It is old in prior art devices, such as shown and claimed in my copending application Serial No. 390,553, filed April 26, 1941, now Patent Number 2,349,209, granted May 16, 1944, and entitled "Control device," to control a diaphragm valve such as a diaphragm gas valve by means of a pilot valve mechanism which is in turn under the control of an electromagnet. Devices of this type are entirely satisfactory when they are so positioned that the noise in the magnet when it is energized as well as the noise made by the magnet as it pulls in and drops out, is not objectionable. In some installations however, it is important that the operation of the mechanism be absolutely silent, and it is therefore a prime object of the present invention to design an operating mechanism for a pilot valve which will be exceedingly quiet in its operation.

An additional object of the invention is to provide a diaphragm valve in which a pilot valve mechanism for operating it and the heat motor for the pilot valve mechanism are mounted directly upon the valve body. An additional object of the invention is to provide such a combination with a manual means for operating the pilot valve in the event that the electric power supply for the heat motor should fail.

A further object of the invention is to operate a control device by means of a heat motor and to provide a slip friction connecting means between them to provide for overrun of the heat motor after the control device has been actuated and to provide for an immediate operation of the control device upon a reversal in the movement of the heat motor.

An additional object of the invention is to operate two control devices by means of the heat motor and to provide a slip friction connection between the heat motor and each of the control devices so that each may be operated independently by the heat motor and the slip friction connections will provide for overrun of the motor after the devices have been actuated.

A further object of the invention is to heat the heat motor by means of an electric circuit and to connect the heat motor with a valve. The circuit in this case is controlled by a condition responsive device which actuates two switches in succession for energizing the heat motor which

then closes a third switch to provide a holding circuit for itself through the first to close switch of the condition responsive device. Both the control valve and the third switch are connected to the heat motor by means of slip friction connecting means.

It is a still further object of the invention to utilize a heat motor of the hot wire type and to provide some means for returning the control device actuated by the heat motor to a safe position in the event that the hot wire should break. In one form of the invention it is contemplated that the hot wire shall be wound around teeth on a fixed member and a movable member and that the movable member should actuate the control device. In this form of the invention the wire used is so stiff that it will not slip with respect to the teeth in the event that the wire should break so that under these circumstances the resultant contraction of the wire upon cooling would return the control device to its safe position. In another form of the invention the movable member which is actuated by means of the hot wire heat motor, is biased by means of a spring for rotation in a direction to place the wire under tension. The spring is connected to the movable member by means of a releaseable connection so that if the movable member should move excessively indicating that the hot wire has broken, the connection would release and disconnect the biasing spring at which time a second spring would take over and return the movable member and hence, the control device to a safe position. In a third form of the invention, the control device is actuated by means of a control arm which is in turn actuated by the movable member. In this case, when the movable member moves excessively, indicating that the hot wire has broken, the actuating arm engages a fixed abutment which causes it to rotate in the opposite direction and return the control device to a safe position.

These and other objects of the invention will readily become apparent to those who are skilled in the art as the following specification is read in the light of the accompanying drawings, in which

Figure 1 is a plan view of a device embodying the various features of my invention, a portion of the circuit connections being shown diagrammatically.

Figure 2 is a side elevation of the embodiment shown in Figure 1.

Figure 3 is a detail view of the slip friction

connections, partly in section, the section being taken along the line 3—3 of Figure 1.

Figure 4 is a detail view of the manual reset mechanism with its strain release feature, with a portion shown in section, the section being taken along the line 4—4 of Figure 3.

Figure 5 is a detail view showing a modified form of my invention for causing a safe movement of the valve mechanism in the event of a breakage in the hot wire.

Figure 6 is a slightly enlarged view of the structure shown in Figure 1, superposed portions thereof being omitted or broken away, and

Figure 7 is a slightly enlarged end view of the upper portion of the structure shown in Figure 1.

Referring now to the drawings, the reference numeral 10 indicates a valve casing which has a diaphragm valve indicated by dotted lines at 11 in Figure 2. A pilot valve device is mounted on top of the valve casing as indicated at 12 and is adapted to control the pressure on top of the diaphragm and therefore control the operation of the diaphragm valve. This much of the construction forms no part of the present invention and is in fact, shown in my copending application, Serial No. 390,553, filed April 26, 1941, now Patent Number 2,349,209, granted May 16, 1944, and entitled "Control device."

The pilot valve mechanism 12 comprises a supply valve and a waste valve which are operated by means of a lever 13 pivotally mounted as shown at 14 and adjustably carrying the two screws 15 and 16. The screw 15 is adapted to open the waste valve as the lever 13 is rotated in a counter clockwise direction as seen in Figure 1 for venting the chamber above the diaphragm and permitting the diaphragm valve to move to open position. The screw 16 is adapted to open the supply valve as the lever 13 is rotated in a clockwise direction admitting pressure to the diaphragm chamber for closing the diaphragm valve. The details of construction of this pilot valve mechanism are fully disclosed in the aforementioned application, Serial No. 390,553, and form no part of the present invention. Each end of the lever 13 is bent inwardly to form a pair of stops 17 to prevent the lever 13 from having any excess rotation after the supply or waste valve has been actuated. The reason for this will appear later.

The lever 13 is provided with an extension 18 which carries a downwardly extending pin 19 which is in turn received by the slot 20 in the right hand end of a floatingly mounted operating arm 21. The arm 21 is carried by means of a slip friction connecting means by the extension 22 on the pivoted bracket 23 which is pivotally mounted as shown at 24 on a plate 25 which is in turn supported by posts 26 on the valve casing 10. Referring to Figures 3 and 6 the slip friction mechanism comprises a graphite washer 28 which is located between the lever 21 and the extension 22 on the bracket 23. The washer 28 is suitably carried by means of the lever 21. The conical member 29 has a small stem which extends through an opening in the extension 22 and also through the washer 28. A bronze spring 30 is anchored at one end in the lever 21 and at its opposite end it engages the point of the conical member 29. The spring 30 a portion of which is broken away in Figure 6 to more clearly show the underlying structure, is tensioned downwardly by means of the screw 31 which enters a tapped hole in the lever 21. By tightening the screw 75

31 the conical member 29 is caused to press the extension 22 and lever 21 together against the graphite washer 28 thereby providing a slip friction connection between the extension 22 and the lever 21.

The pivoted bracket 23 carries a plate 32 formed of some insulating material such as "Bakelite." This plate is provided with a plurality of teeth 33. A second insulating plate 34 is suitably fixed to member 58 carried by the plate 25. The insulating plate 34 is also provided with a plurality of teeth 35. One end of a thin metal wire is securely wrapped around a screw 37 which is fixed to the insulating plate 34. This wire is then wrapped around alternate teeth on the two insulating plates 32 and 34 to form a plurality of strands of a hot wire thermal member 38. The other end of the wire is then brought back against the insulating plate 34 and is securely fastened to a second screw located below the screw 37. This wire is chosen so as to have sufficient resistance so that when an electric current is passed through it, it will heat up appreciably and expand. The pivoted bracket 23 is provided with a finger 35 over which is hooked one end of a tension spring 39, the other end being hooked to an extension 27 on the fixed member 58. The effect of this spring is to tend to rotate the pivoted bracket 23 in a clockwise direction and therefore maintain the strands of wire under tension. It will thus be seen that as the wire 38 is heated up the strands will expand and permit the bracket 23 to rotate in a clockwise direction under the influence of the spring 39, but as these strands contract they will rotate this bracket in a counter-clockwise direction.

As the bracket 23 rotates in a clockwise direction the extension 22 will carry the floating lever 21 with it and cause it to rotate lever 13 in a counter-clockwise direction whereupon the screw 15 will open the waste valve and permit the diaphragm valve to open. It will be noted that the lever 13 has only a slight rotative movement after which one or the other of the turned ends 17 will engage the pilot valve housing 12 and prevent further rotation. Further rotation of the bracket 23 will then be permitted due to the slip friction connection between the extension 22 and the floating lever 21. Therefore, as soon as the direction of the rotation of the bracket 23 is reversed the lever 13 will immediately start to move and actuate the pilot valve mechanism. Then after further movement of the lever 13 is prevented, the slip friction mechanism between the extension 22 and the floating lever 21 will again function to permit further movement of the bracket 23. Thus, it will be seen that the slip friction mechanism provides for actuation of the pilot valve mechanism just as soon as the bracket 23 reverses in its movement and that this slip friction mechanism will then provide for an overrun movement of the bracket 23. It will be understood, of course, that when the bracket 23 rotates in a counter-clockwise direction that it will carry the floating lever 21 with it and cause the lever 13 to rotate in a clockwise direction whereupon the screw 15 will permit closure of the waste valve and the screw 16 will open the supply valve to close the diaphragm valve.

The pilot valve device 12 is one of two control devices operated by the hot wire thermal member 38. The other control device is a switch which will now be described.

A suitable insulating block 40 is mounted on

the valve casing 10 by means of the screws 41. A movable contact arm 42 is pivoted as shown at 43 to a bracket 44 which is in turn, suitably carried by the insulating block 40. A stationary contact 45 is also carried by the insulating block 40 and so positioned as is best shown in Figures 1 and 6, as to cooperate with the movable contact arm 42. The engagement of the movable contact arm 42 with the stationary contact member 45 limits the rotation of the arm 42 in one direction whereas the adjustable screw 46 which is carried by the bracket 44 limits the rotation of this contact arm 42 in the opposite direction. The contact arm 42 is provided with an extension 47 which carries a pin 48 extending downwardly into a slot into the insulating member 49. A portion of the extension 47 is broken away in Figure 6 to more clearly show the slotted insulating member 49. This member 49 is carried by the bracket 23 by means of a slip friction connection.

Referring particularly to Figure 3, it will be seen that this slip friction connection comprises a metal cup 50 which is carried by the bracket 23 and which in turn carries a graphite washer 51. The insulating member 49 carries a small bronze plate 52 which engages the surface of the friction washer 51. A conical member 53 is provided with a stem, not shown, which extends downwardly through the member 49 and through the graphite washer 51. This conical member 53 is forced downwardly by means of the bronze spring 54 which is anchored in one end in the bracket 23 and which bears at its other end against the conical member 53. The force with which this member bears against the conical member 53 is determined by means of the screw 55 which engages the bronze spring 54 and which is screw-threadedly received in the bracket 23. In this case, the friction is between the graphite washer 51 and the bronze plate 52. It will be understood, of course, that by tightening the screw 55 the pressure is increased between the bronze plate 52 and the graphite washer 51 and therefore, the amount of the friction is increased.

A clockwise rotation of the bracket 23 will cause a counter-clockwise rotation of the contact arm 42 and a resultant closure of the switch 42, 45. After this switch has been closed, further movement of the bracket 23 is permitted by means of the slip friction connection. Immediately the bracket 23 starts rotating in the opposite direction, the switch 42, 45 will open and after a very slight rotation of the contact arm 42 its movement will be stopped by engagement with the screw 46. Further movement of the bracket 23 will again be permitted by the slip friction connection. Thus, it will be seen that the switch 42, 45 is always actuated immediately upon a reversal of movement of the bracket 23.

One end of the wire forming the hot wire thermal member 38 is connected to a terminal screw 58 on the bracket 44 by means of the conductor 59. The bracket 44 is connected by means of the conductor 60 to a stationary contact 61. The other end of the wire 38 is connected by means of conductor 62 to the secondary winding 63 of a step-down transformer 64 which has a primary winding 65. The primary winding 65 is, of course, adapted to be connected to a suitable source of power. Conductor 66 connects the other side of the secondary winding 63 to a second stationary contact 67. The circuit across the two stationary contacts 61 and 67 may be controlled by any suitable device. For the purposes of illus-

tration, this device is shown as comprising a thermostat 68 which is formed by a bimetal member 70 which is fixed at one end and carries a resilient contact blade 71 and a second contact blade 72 at its free end. The arrangement is such that upon a decrease in temperature the contact blade 71 will first engage the contact 67 and then at a slightly lower temperature the contact blade 72 will engage the contact 61. The bimetallic member 70 is connected to the stationary contact member 45 by means of conductor 73.

The operation of the device as far as it has been described, should now be apparent. When the thermostat 68 is satisfied, the bimetallic member 70 will maintain the two contact blades 71 and 72 in open circuit position. Under these circumstances, the circuit to the hot wire thermal member 38 will be broken and this member will therefore be cold in its contracted position. It will therefore have rotated the bracket 23 to its counter-clockwise position and this bracket will have moved the floating lever 21 to a position where it has caused the screw 16 to open the supply valve to bleed pressure into the diaphragm chamber and therefore close the main diaphragm valve. On a decrease in temperature at the thermostat 68 the bimetal member 70 will contract and cause the contact blade 71 to engage the stationary contact 67. This operation will not result in an establishment of any circuit due to the fact that the bracket 23 in its counter-clockwise position maintains the contact blade 42 in open circuit position. Therefore, the temperature will continue to decrease until the contact blade 72 is brought into engagement with the stationary contact 61. This will establish a circuit from one side of the secondary winding 63 through conductor 66, contact 67, contact blades 71 and 72, contact 61, conductor 60, bracket 44, terminal screw 58, conductor 59, hot wire 38, and conductor 62 back to the other side of secondary winding 63. This will result in a flow of current through the hot wire thermal member 38 which will then increase in temperature and expand permitting the biasing spring 39 to rotate the bracket 23 in a clockwise direction. This bracket 23 will then carry the floating lever 21 downwardly as seen in Fig. 1, thus causing the screw 16 to permit the supply valve to close and causing the screw 15 to open the waste valve. This will bleed the diaphragm chamber and permit the main diaphragm valve to open. Rotation of the bracket 23 in a clockwise direction also causes a counter-clockwise rotation of the contact arm 42 which will result in its being brought into engagement with the stationary contact member 45. This sets up a holding circuit from one side of the secondary winding 63 through conductor 66, contact 67, contact blade 71, bimetallic element 70, conductor 73, stationary contact member 45, contact arm 42, bracket 44, terminal screw 58, conductor 59, wire 38 and conductor 62 back to the other side of secondary winding 63. It will thus be apparent that the circuit through the hot wire 38 will remain closed until the temperature rises sufficiently to cause the bimetallic element 70 to separate the contact blade 71 from its stationary contact 67. When this action takes place the circuit to the hot wire element will be broken and it will therefore cool and contract causing a counter-clockwise rotation of the bracket 23 and a resultant movement of the floating lever 21 back to its original position in which it permits the screw 16 to close the waste valve and causes the screw 16 to open the supply valve, thereby bleed-

ing pressure fluid into the diaphragm chamber and causing a closure of the main diaphragm valve. At the same time, this counter-clockwise rotation of the bracket 23 causes a clockwise rotation of the contact arm 42 which moves this contact arm to open circuit position. Therefore, before the circuit may again be closed to the hot wire element 38, both the contact arms 71 and 72 must be brought into engagement with their stationary contacts.

As stated above, both the contact arm 42 and the pilot valve actuating lever 18 have relatively limited movement and the two slip friction mechanisms between them and the bracket 23 permit overrun movement of the bracket 23. It will also be apparent that both of these mechanisms will be actuated as soon as there is a reversal of movement of the bracket 23. This provides for a positive operation of these mechanisms substantially immediately upon the opening or closing of the circuit through the hot wire thermal element 38.

In valves of this type, it is desirable to provide some means for manually operating the pilot valve mechanism in the event that the electrical power for operating this mechanism should fail for some reason. Thus, a means has been shown in the form of the lever 88 which is pivotally mounted upon a bracket 81 suitably fixed to the valve casing 10. This member is provided with what is known as a scissors-type strain release formed by a pair of levers 82 and 83 mounted concentrically with the lever 88. A biasing spring 84, connected between one end of these levers, biases them against a stop 85 mounted on the lever 88.

The left hand end of the floating lever 21 is provided with a downwardly extending portion 86 which extends between the two ends of the levers 82 and 83 opposite the biasing spring 84. Thus, a rotation of the lever 88 in either direction will cause one or the other of the two levers 82 and 83 to engage the projection 86 and cause rotation of the lever 21 and a consequent actuation of the pilot valve mechanism. After the lever 21 has been stopped from further rotation by the pilot valve mechanism, further movement of the lever 88 will be permitted by the elongation of the spring 84. In other words, the lever 21 is driven by the lever 88 through the spring 84 which acts as a strain release when further movement of the lever 21 is not permitted.

It will be noted also that the manual lever 88 acts directly upon the lever 21 and that movement of this lever is permitted with respect to the bracket 23 by means of the slip friction connection between the two. Thus, manual actuation of the pilot valve mechanism does not affect the thermal member 38 nor does it place any strain whatever thereon.

It would be dangerous if it were possible for the breakage of the wire of the hot wire thermal member 38, due to burning out or for some other reason, to permit the pilot valve mechanism to remain in a position indefinitely to cause the main diaphragm valve to remain open. It is necessary, therefore, to provide some means for returning this pilot valve mechanism to a safe position in the event of such breakage. There are several ways in which this could be done. In the first place, the wire for the hot wire thermal member 38 could be chosen to be relatively stiff so that when it was wound around the teeth 33 and 36 as shown in Figure 2, it would not slip with respect thereto upon breakage of the wire. Thus, if the wire were to break at one point, the circuit

through the wire would be broken and the wire would cool and contract, and if the wire were stiff enough the strands which were intact would act to rotate the bracket 23 in a counter-clockwise direction and cause the pilot valve mechanism to return to its safe position in which it closes the waste valve and opens the supply valve to cause closure of the main diaphragm gas valve. Such an arrangement is shown in Figure 1.

If a wire of this type were not used, the finger 35 upon which one end of the biasing spring 39 is hooked, could be shaped as shown in Figure 1. Then upon breakage of the wire 38 the biasing spring 39 would rotate the lever 23 an abnormal amount in a clockwise direction following which the spring 39 would merely slip off the end of the finger 35. When this has taken place a second spring 88 will come into play to return the bracket 23 to its counter-clockwise position and hence, move the pilot valve mechanism to its safe position. This spring 88, of course, would have to be weak enough to be overpowered by the main biasing spring 39 but strong enough to return this bracket to its counter-clockwise position in the event that the spring 39 should be disconnected from the bracket 23.

Another way of solving this problem is to provide a pin 89, as shown in Figure 5. This pin 89 is fixed to the valve casing 10 and when the bracket 23 is rotated in a clockwise direction an abnormally large amount which could be caused only by breakage of the wire of the hot wire thermal member 38, a mid-portion of the floating lever 21 would engage the pin 89 so that as the left hand end of this lever was carried downwardly due to clockwise rotation of the bracket 23 the lever 21 would rotate about the pin 89 to cause a clockwise rotation of the lever 18 and therefore, a movement of the pilot valve mechanism to a safe position.

It will be noted that the entire mechanism with the exception of the condition responsive device is relatively small and compact and it is mounted directly upon the valve body, and being of the heat motor type, would be extremely silent in operation. It will be further noted that this mechanism provides for manual operation in the event of power failure and provides for the movement of the pilot valve mechanism to a safe position in the event that the hot wire of the thermal motor should burn out.

As various changes and modifications of this invention will undoubtedly occur to those who are skilled in the art, I desire it to be understood that I intend to be limited only by the scope of the appended claims and not by the specific embodiments which have been shown merely for the purposes of illustration.

I claim as my invention:

1. In a device of the character described, in combination, a movably mounted control device, stop means for determining two positions of operation of said control device, a heat motor including a thermally responsive member adapted to be connected to a power supply, an operator for said control device, connections between said heat motor and operator whereby said heat motor operates said control device, said connections including two elements connected by a slip friction connection so as to provide for overrun of the heat motor after said control device has been moved to one of its positions, and manual means associated with said operator for moving said control device in the event of a failure in the power supply for said heat motor, said manual means

comprising a manually movable member so connected to said operator that movement of said manually movable member causes movement of said control device without affecting the position of said heat motor.

2. In a device of the character described, in combination, a movably mounted control device, stop means for determining two positions of operation of said control device, a heat motor including a thermally responsive member adapted to be connected to a power supply, an operator for said control device, connections between said heat motor and operator whereby said thermally responsive member operates said control device, said connections including two elements connected by a slip friction connection so as to provide for overrun of the heat motor after said control device has been moved to one of its positions, manual means associated with said operator for moving said control device in the event of a failure in the power supply for said heat motor, said manual means comprising a manually movable member connected to said operator for movement thereof without causing movement of said heat motor, and strain relief means associated with said manual means for limiting the amount of force which can be transmitted to said control device.

3. In a device of the character described, in combination, a movable member biased for movement from a first to a second position, means including a thermal element of the hot wire type restraining said member from such movement and holding it in said first position when said thermal element is cold, a control device having corresponding first and second positions of operation, operative connections between said movable member and said control device, said movable member moving said control device from first to second operative position as a result of its bias upon heating and expansion of said hot wire thermal element, and means for moving said control device from second to first position in the event of the breakage of the wire of said hot wire thermal element and independently of the cooling and contracting urge of said broken thermal element.

4. In a device of the character described, in combination, a movable member biased for movement in a direction from a first to a second position, means including a thermal element of the hot wire type restraining said member from such movement and holding it in said first position when said thermal element is cold, a control device having corresponding first and second positions of operation, operative connections between said movable member and said control device, said movable member moving said control device from said first to said second operative position as a result of its bias upon heating and expansion of said hot wire thermal element, said operative connections including an arm rotatably connected to said movable member, means resisting relative rotations between said member and arm, and means engaged by said arm for causing such relative rotation to move said control device from said second to said first position in the event of breakage of the wire of said hot wire thermal element.

5. In a device of the character described, in combination, a movable member biased for movement in one direction, means including a thermal element of the hot wire type restraining said member from such movement and holding it in a first position when said thermal element is cold, a control device having two positions of operation, an arm operatively connected to said

control device, slip friction means connecting said arm to said movable member whereby said control device may be operated from one operative position to another by said movable member upon expansion of the hot wire of said thermal element, and stationary means engaged by said arm to cause reverse movement thereof and movement of said control device back to its said one operative position in the event that said movable member moves excessively due to breakage of the hot wire of said thermal element.

6. In a device of the character described, in combination, a control device movable between a safe position and an active position, said device being biased to said active position, means including a thermal element of the hot wire type connected by a lever to said device for restraining said device and holding it in said safe position when said thermal element is cold and for expanding when hot to permit said control device to be moved to said active position, and a stop in the path of said connecting lever and effective in the event of excessive movement of said lever as a result of the breakage of said hot wire thermal element to change the character of said movement so as to cause said control device to be moved to said safe position.

7. In a device of the character described, in combination, a control device movable between a safe position and an active position, said device being biased to said active position, means including an electrically energized thermal actuated element of the hot wire type for restraining said device and holding it in said safe position when said thermal actuated element is cold and for expanding when hot to permit said control device to be moved to said active position, said thermal element comprising a plurality of substantially parallel loops, and means effective in the event of the breakage of any loop of said hot wire thermal actuated element to permit movement of said control device to said safe position without causing corresponding movement of said thermal actuated member.

8. In a device of the character described, in combination, a movably mounted member, a biasing spring therefor, means connecting said spring to said member for biasing it for movement in one direction, means including a thermal element of the hot wire type restraining said member from such movement and holding said member in a first position when said thermal element is cold, a control device having first and second positions of operation, operative connections between said movable member and said control device, said movable member moving said control device from first operative position to second operative position as a result of its bias upon heating and expansion of said hot wire thermal element, said movably mounted member and said thermal element being constructed and arranged to permit the return movement of said movable member to its first position upon breakage of said hot wire thermal element and independently of the cooling and contracting urge and movement of said broken thermal element.

9. In a control device, a heat motor operably associated with said control device, means for supplying power for said heat motor, slip friction connecting means between said heat motor and said control device whereby the latter is operated by the former, said connecting means being disposed to transmit movement in alternate directions to the control device concurrently with the initiation of similar movement of said heat motor.

means permitting movement of said control device in a closing direction and movement in opening direction of said heat motor in the event of breakage of said motor, and manual means for operating said control device in the event that the power to said heat motor should fail, said manual means comprising a manual operator connected to said control device independently of said slip friction connecting means so that movement of said manual operator causes movement of said control device without affecting the position of said heat motor.

10. In a control device, a pilot valve means, a heat motor operably associated with said pilot valve means, said heat motor comprising an expandable wire, electrical means for heating said expandable wire, a fixed member having a plurality of teeth, one end of said wire being fastened to the said fixed member, a rotatable member having a plurality of teeth, said wire being passed around said teeth alternately on said rotatable member and said fixed member to form a plurality of substantially parallel strands, the other end of said wire being fastened to said fixed member, means biasing said rotatable member for rotation in a direction to tension said strands whereby said member will rotate in that direction when said wire is expanded by a passage of current therethrough, a slip friction connection between said rotatable member and said pilot valve means so that said pilot valve means is quickly moved upon a change in the condition of energization of said wire, and stop means operable under certain conditions to reverse the movement of said pilot valve while permitting forward movement of said rotating member.

11. In a device of the character described, in combination, a control device movable between a safe position and an active position, said device being biased to said active position, means including a thermal actuated element of the hot wire type for restraining said device and holding it in safe position when said thermal actuated element is cold and for expanding when hot to permit said control device to be moved to said active position, means limiting the movement of

said control device without limiting the movement of said thermal actuated element, and means for causing said control device to be moved in a reverse direction to said safe position in the event of the breakage of said hot wire thermal actuated element while said thermal actuated element may continue its movement toward active position.

12. In a device of the character described, in combination, a control device movable between a safe position and an active position, a relatively powerful biasing means biasing said control device to said active position, means including a thermal actuated element of the hot wire type for restraining said device and holding it in said safe position when said thermal element is cold and for expanding when hot to permit said control device to be moved by said first named biasing means to said active position, said thermal actuated element and said control device being constructed and arranged to permit movement of said control device to safe position in the event of breakage of said hot wire thermal element without corresponding movement of said thermal actuated element.

13. In an automatic control system, in combination, a movably mounted control valve, means limiting the movement of said control valve between a first position and a second position, means biasing said control valve toward first position, a heat motor including a movable member, electric circuit means for heating said motor, a switch connected in said electric circuit, operative connection means between said motor and said switch and said valve by means of which said heat motor operates said switch and said valve concurrently, said connection means being disposed to permit overrun of said heat motor after said valve and said switch have been moved to operative position, and means operable under certain conditions for permitting said control device to move from second to first position independently of the movement of the movable member of said heat motor.
